UNITED STATES PATENT OFFICE.

PETER J. KEYMEL, OF BERRYVILLE, VIRGINIA, ASSIGNOR OF ONE-HALF TO H. C. WARDEN, OF BERRYVILLE, VIRGINIA.

PROTECTIVE CAP FOR FRUIT CONTAINERS.

Application filed January 2, 1923. Serial No. 610,237.

To all whom it may concern:

Be it known that I, PETER J. KEYMEL, a citizen of the United States, residing at Berryville, in the county of Clarke and State of Virginia, have invented certain new and useful Improvements in Protective Caps for Fruit Containers, of which the following is a specification.

This invention relates to a cap for shipping containers and particularly to a construction adapted for application to a receptacle for the shipping and storage of fruit.

In the prior art it has been customary to provide a loose cushioning cap disposed beneath the cover of the container but such cap has been found liable to displacement when the cover is applied and also leaves the contents of the container exposed at the edges thereof where they are liable to be bruised or injured in the lateral movement of the cover when placed in position and when the containers are stacked as in shipment or storage. It has also been customary to secure to the cover a packing material but this structure only protects the contents of the receptacle immediately beneath the same.

The present invention, therefore, provides an improved form of dished cap which not only cushions the contents of the container against downward pressure upon the cover but also against any lateral or side movement of such cover and further provides means by which the cap is securely held in position against displacement in the application of the cover while the dished portion thereof is raised above the fruit.

This dished form of cap is also adapted for convenient nesting in packing and is adapted to be produced by a single machine operation.

Other and further objects and advantages of the invention will be hereinafter set forth and the novel features thereof defined by the appended claims.

In the drawing:

Figure 1 is a perspective view of the invention.

Figure 2 is an enlarged cross section showing the application of the cap.

Figure 3 is a fragmentary plan view of the cap.

Figure 4 is a similar view of a modified form thereof.

Figure 5 is an edge view looking from the left of Figure 2.

Like numerals refer to like parts in these several figures of the drawings:

The numeral 10 designates a container or receptacle of any desired character and is herein shown as comprising the basket type ordinarily used for fruit and vegetable shipments. The cover 11 for this type of container is usually of the slatted character 65 and has projecting securing portions 12 adapted to be disposed beneath the handles 13 of the container. This cover is provided with a circular rim 14 secured thereto which is adapted to rest upon the upper edge 15 70 of the container.

The cap 16 may be formed of any desired material and is preferably provided with cushioning means such as the corrugations 17 formed of corrugated board or paper and carried by a base sheet 18. The body of the cap is provided at its edges with a lateral portion 19 which terminates in a securing edge 20 disposed in the plane of the body, which affects the cupped or dished 80 form of the cap raising the body thereof above the upper edge of the container. This securing edge may be formed in any desired manner but is preferably radially corrugated as shown in Figures 2 and 5, in order 85 to provide a cushioning face to protect the contents of the receptacle against injury in the side movement of the cover incident to its application or when being handled or shipped, as indicated by dotted lines in Figure 2. In the former use of cushioning caps such movement of the cover was liable to bruise the fruit at the edges of the basket thus injuring its appearance and affecting the sale value thereof which is largely gov-

erned by the appearance of the contents when the cover is removed. This side movement of the cover not only occurs in its application but when a number of baskets are stacked there occurs a rocking play during shipment which causes the edge of the cover to contact with the fruit in the basket and this invention seeks to fully protect the contents against such injury and also against the yielding of the cover due to the 105 weight of superposed receptacles.

The direction and character of corrugations used in the cap may be varied, for instance in Figure 4 the corrugations 21 in the body are concentric in location while those at the securing edge 22 are radial as in the preferred form of the invention.

While the details of the invention have been specifically shown and described, still it is not confined thereto as changes and alterations may be made without departing from the spirit of the invention as defined by the following claims.

What I claim is:

1. As a new article of manufacture, a protective cap for containers of fruit or the like having a cushioning body and a peripheral flange adapted to rest upon the edge of the container and forming a seat for and coextensive with the cover thereof.
2. As a new article of manufacture, a protective cap for fruit containers having a dished cushioning body adapted to coact with a container cover to centralize and maintain the cap with respect to the container, said cap being provided with a

peripheral flange upon which the said cover seats to protect the contents of the container from contact with the cover.

3. As a new article of manufacture, a protective cap for fruit containers or the like comprising a dished corrugated body adapted when in inverted position to coact with the container cover, said cap having a horizontal peripheral flange similarly corrugated to provide a cushioned seat for the cover.

4. A container cap having a dished cushioning body provided with parallel corrugations and a securing edge formed with radial corrugations extending from the parallel corrugations.

5. The combination of a container, a cover therefor having a rim to rest upon the upper edge of the container, and a cushioning cap dished to extend within said cover and having a securing edge disposed to extend between said cover rim and the container edge.

In testimony whereof I affix my signature.
PETER J. KEYMEL.
